UNITED STATES PATENT OFFICE

IGNATZ GLANSCHNIG, OF GARY, INDIANA, ASSIGNOR OF ONE-HALF TO ANTON KAZLAWSKI, OF GARY, INDIANA

AEROPLANE PROPELLER

Application filed August 16, 1929. Serial No. 366,368.

This invention relates to aeroplane propellers and an object of the invention is to provide a propeller that creates the maximum of pulling power with a relatively small amount of resistance, by reason of the fact that at the hub the blades of the propeller are constructed upon the principle of a screw to permit the air to pass through without obstruction.

10 Another object of the invention is to provide a propeller that aids in the cooling of the motor, that provides a rolling blade which not only makes the propeller stronger, but reduces the resistance against the revolving of the propeller.

Further objects of the invention are to provide in a manner as hereinafter set forth, a propeller of the character referred to, that is strong, compact and durable, very reliable in its intended purpose, very simple in its method of assembly, adaptable for installation to any type drive shaft, and is comparatively inexpensive to manufacture and assemble.

25 With the foregoing and other objects in view, the invention consists of a novel construction, combination and arrangement of parts, as will be more particularly described and illustrated in the accompanying drawings, wherein is disclosed an embodiment of the invention, but it is to be understood that changes, variations and modifications may be resorted to without departing from the spirit of the claims hereto appended.

35 In the drawings, wherein like reference characters denote corresponding parts throughout the several views:

Figure 1 is a front elevation of the propeller with the hub cap removed and showing the propeller revolving clockwise in the direction of the arrows.

40 Figure 2 is a top plan view of the propeller in the assembled relation on the crank shaft.

45 Figure 3 is a side view of the propeller showing the outer or free end of one of the blades.

Figure 4 is an enlarged sectional detail view at the hub portion of the propeller.

50 Figure 5 is a vertical section in detail

taken substantially on line 5—5 of Figure 4 and looking rearwardly.

Figure 6 is an enlarged plan view of the hub cap.

55 Figure 7 is a fragmentary vertical section in detail taken through the hub cap and hub illustrating the latch in locked position.

Figures 8, 9 and 10 are sections taken substantially on line 8—8, 9—9, and 10—10 of Figure 1, illustrating the rolling pitch of the blades.

60 Figures 8a, 9a, and 10a are diagrammatic views taken substantially on lines 8—8, 9—9, and 10—10 of Figure 1, illustrating the angular pitch of the blade from the end to the hub thereof, and,

65 Figure 11 is a fragmentary plan view of a modified form of the invention.

Referring to the drawings in detail, 15 70 indicates a solid conical shaped hub cap formed of aluminum. On the base of the hub cap there is formed an annular groove 16 adjacent the periphery thereof to provide for countersinking the forward ends of 75 the hub bolts to be presently described. The outer walls of the hub cap extend slightly below the face of the base for the purpose of forming an annular flange 17. A bolt 18 has the head end cast integral in the hub 80 cap with the threaded end projecting from the base along the axis of the cone. The flange 17 has a slot 19 extending therethrough and a spring latch 20 is held in superimposed position over the slot by a 85 rivet or holdfast device 21 secured at one end of the latch and to the wall of the hub cap. The other free end of the latch is free to be flexed.

80 An arcuate shaped lug 22 is secured to the inner face of the latch by a rivet 23 and is of such thickness that it normally projects radially from the inner face of the flange 17 by the action of the spring latch so that it will be detachably locked in a recess on the hub to be presently described. The hub cap 15 is adapted to have the apex leading and projecting forwardly from the propeller blades, with the base thereof to be the trailing portion, and when the hub cap 100

15 is connected to the hub of the propeller a continuous conical shaped hub is formed.

The propeller blades and the hub are preferably cast integral and formed of an aluminum copper alloy, but it is also within 5 the contemplation of this invention to form the same of wood. In forming the alloy, it has been found that one pound of copper added to the aluminum of each propeller is sufficient. Care must be taken to add the 10 copper in the form of a fine wire so as to make a homogeneous casting. If lump copper were used in the alloy there would be segregated areas of copper in the casting 15 and owing to the difference in weight of the copper there would be an unbalanced propeller.

The segregation would be due to the different melting point of aluminum and copper. The better way to form the alloy would 20 be to mix the aluminum and copper together in the molten states.

The hub of the propeller is indicated at 24 and is of frusto-conical shape with the 25 frustum leading. The leading periphery adjacent the forward face is formed with an annular shoulder 25 over which is seated the flange 17 on the hub cap. Extending axially from the leading face of the hub is 30 a peripherally threaded circular socket 26 that is adapted to receive the threaded projecting end of the bolt 18. The bolt is threaded in such a manner that it turns in the threads of the socket 26 opposite to the 35 rotation of the propeller, to eliminate the possibility of the hub cap being detached from the revolving hub.

Spaced radially from the cavity 26 is an annular series of openings 27 through which 40 extend a plurality of bolts 28. The forward ends of the bolts are threaded and have nuts 29 thereon which are seated in the annular groove 16, when the hub cap 15 is attached to the hub 24. The series of bolts 45 28 have the heads 30 thereof coupled in an abutting relation to the flange 31 of the crank shaft 32 which may lead from any prime mover such as an internal combustion engine. When the hub cap 15 is screwed 50 into the socket 26 and the flange 17 is seated tight against the shoulder 25, a cavity 22' formed on the periphery of the shoulder 25 provides an alined seat for the lug 22. When the lug 22 snaps into the seat 22' the 55 cap is locked to the hub and requires the latch 20 to be flexed before the cap can be removed.

A pair of propeller blades, indicated generally as 33 and 34, project diametrically 60 from opposite sides of the hub, the edges at the free ends of the blades being rounded as in Figure 1, but it is within the contemplation of my invention to modify the ends of 65 the blades to a curve having a radius equiv-

alent to the length of the blade, as in Figure 11.

Beginning at its outer end, each blade has a pitch of sixty-five degrees with respect to the plane of rotation of the propeller, and 70 the blade rolls or twists with decreasing pitch toward the hub. Adjacent the hub the blades have a pitch of thirty degrees with respect to the plane of rotation of the propeller. 75

This rolling or twist of the blades is illustrated in the diagrammatic views, 8a, 9a, and 10a. As the hub is approached the twisted blades pass through less space and 80 therefore the decreased pitch causes the air currents to pass through the vortex around the hub of the propeller, thereby eliminating backpush found in many propellers.

It will be understood that the blades are relatively inclined in opposite directions from the plane of rotation of the propeller. In the model tested, it was found that the roll of the propeller blade as above described gives it greater tensile strength. By using a testing apparatus, it was found 85 that the propeller formed in accordance with the present invention made twelve revolutions per minute around a circle having a diameter of twenty-five feet while a representative model of propellers now in use 90 made only five revolutions per minute around the same circle with the same driving power. 95

Beginning at the outer end the blades 100 thicken uniformly to the point where each blade merges with the hub 24. The thickening of each blade is clearly illustrated in Figures 8, 9 and 10 of the drawings which 105 illustrate sections taken on lines 8—8, 9—9, and 10—10 of Figure 1. In a conventional sized propeller in accordance with the present invention, the blade is four inches wide at the free end to approximately one-third the distance to the hub and from the latter point, the blade should taper regularly 110 from four inches to three and one-half inches wide where the inner end merges with the hub.

Moreover, in a conventional sized propeller in accordance with the present invention, there is a space of two times three or more inches between the blades at the hub 115 to permit the passage of air through the blades at the hub.

Referring particularly to Figure 9 where 120 a cross section of a blade is shown, looking toward the hub, the trailing face is indicated as 35, and at the rear of the forward edge of the blade, the face is curved as at 36, the remaining portion of the trailing face being flat. The curved portion 36 extends from the tip of the blade to the hub 125 of the propeller. The leading face 37 of each blade is also flat throughout the length 130 of the blade, except for a rounded or curved

part 38 at the rear edge of this leading face, which curved part also extends from the tip of the blade to the hub of the propeller.

Thus the leading edge 39 of the leading face, and the trailing edge 40 of the trailing face of each blade is flat, while the rear trailing edge, of the leading face and the front trailing edge of leading face are rounded.

10 The two faces 35 and 37 are in parallelism throughout the length of the blade, regardless of the thickness of the blade, and of the twist or acuteness of the angle or pitch of the blade.

15 The blade with parallel and substantially flat faces is thus given a maximum pulling power, while the uniform width of these faces also adds to the pulling power, which power is present from the tip of the blade

20 to the hub of the propeller, i. e. throughout the length of the blade. The curves 36 and 38 at the leading and trailing edges of the blades enable the blades to pull more easily and to cut more easily through the air.

25 Having described my invention, what I claim is:

1. An aeroplane propeller comprising a hub, a pair of blades formed integral with the hub and disposed on the diametrically

30 opposite sides thereof, said blades inclining in opposite directions from each other, each of said blades rolling from an angle of sixty-five degrees with respect to the plane of the rotation of the propeller on its outer end

35 to an angle of thirty degrees at a point where each blade merges with the hub, and means on the hub for connection to a drive shaft of a prime mover, the margin at the upper edge of each blade flat on the leading face and curved on the trailing face and the margin at the lower edge of each blade curved on the leading face and flat on the trailing face to provide pulling power the entire width of the blade from end to hub.

40 2. An aeroplane propeller comprising a hub, blades formed integral with the hub and disposed on the diametrically opposite sides thereof, said blades inclining in opposite directions from each other, each of said

45 blades rolling from an angle of sixty-five degrees with respect to the plane of rotation of the propeller on its outer end to an angle of thirty degrees at a point where each blade merges with the hub, and means on the hub

50 for connection to a drive shaft of a prime mover, the margin at the upper edge of each blade flat on the leading face and curved on the trailing face and the margin at the lower edge of each blade curved on the leading face and flat on the trailing face to provide pulling power the entire width of the blade from end to hub.

55 3. An aeroplane propeller comprising a hub, blades formed integral with the hub on

60 the diametrically opposite sides thereof and

inclining in opposite directions from each other, each of said blades rolling from an acute angle with respect to the plane of rotation of the propeller on the end of the blade to an acute angle of lesser degree where the blades merge with the hub and means on the hub for connection to a crank shaft of a prime mover, the margin at the upper edge of each blade flat on the leading face and curved on the trailing face and the margin at the lower edge of each blade curved on the leading face and flat on the trailing face to provide pulling power the entire width of the blade from end to hub.

4. An aeroplane propeller comprising a hub, to form a continuous cone when assembled on the hub, blades formed integral with the hub on the diametrically opposite sides thereof and inclining in opposite directions from each other, each of said blades

80 rolling from an acute angle with respect to the plane of rotation of the propeller on the end of the blade to an acute angle of lesser degree where the blades merge with the hub and means on the hub for connection to a crank shaft of a prime mover, the margin at the upper edge of each blade flat on the leading face and curved on the trailing face and the margin at the lower edge of each blade curved on the leading face and flat on the trailing face to provide pulling power the entire width of the blade from end to hub.

85 5. A propeller having a plurality of blades each twisted to provide an angle of attack substantially throughout the length of the blade, said blades each having parallel, flat, leading and trailing faces, the forward edge of the trailing face being rounded

90 and the rearward edge of the leading face being rounded substantially throughout the length of the blade.

95 6. A propeller having a plurality of blades each twisted to provide an angle of attack substantially throughout the length of the blade, said blades each having parallel, flat, leading and trailing faces, the forward edge of the trailing face being rounded

100 and the rearward edge of the leading face being rounded substantially throughout the length of the blade.

In testimony whereof I affix my signature.
